UNITED STATES PATENT OFFICE.

WILLIAM L. FRANKS, OF ROCK ISLAND, ILLINOIS.

DESIGN FOR A LAMP-SHADE.

47,153.

Specification for Design.

Patented Mar. 30, 1915.

Application filed January 2, 1915. Serial No. 276. Term of patent 14 years.

To all whom it may concern:

Be it known that I, WILLIAM L. FRANKS, a citizen of the United States, residing at Rock Island, in the county of Rock Island, State of Illinois, have invented a new, original and ornamental Design for Lamp-Shades, of which the following is a specification, reference being had to the accompanying drawings, forming part thereof, in which—

Figure 1 is an end view of my new design of a lamp shade, Fig. 2 is a bottom plan view thereof. Fig. 3 is a similar view from a slightly different angle.

The distinguishing ornamental feature of my design of lamp shade resides more particularly in the gentle slope of its forward face as at *a* dropping abruptly as at *b* and terminating in the flanged edge *c* together with the corrugations *d* in the rear wall.

I claim;

The ornamental design for a lamp shade as shown and described.

WILLIAM L. FRANKS.
